(57) **CLAIM**

The ornamental design for a string trimmer accessory, as shown and described.

DESCRIPTION

FIG. 1 is a top perspective view of a string trimmer accessory showing my new design;

FIG. 2 is a left view thereof;

FIG. 3 is a right view thereof;

FIG. 4 is a front view thereof;

FIG. 5 is a rear view thereof;

FIG. 6 is a top plan thereof; and,

FIG. 7 is a bottom plan view.

In the above drawings, the broken lines and areas within the broken lines represent portions of the article and form no part of the claimed design.
